UNITED STATES PATENT OFFICE.

JERRY M. LAPHAM, OF MARIETTA, OHIO.

WASHBOARD.

1,237,066.

Specification of Letters Patent. Patented Aug. 14, 1917.

Application filed March 20, 1917. Serial No. 156,078.

To all whom it may concern:

Be it known that I, JERRY M. LAPHAM, a citizen of the United States, residing at Marietta, in the county of Washington and 5 State of Ohio, have invented new and useful Improvements in Washboards, of which the following is a specification.

The present invention relates generally to wash boards.

10 The primary object of the invention resides in the provision of a wash board which is simple in construction, durable in use, and one wherein the rubbing board is so constructed and mounted to the wash board, to 15 quickly and easily adapt the same for cleansing coarse and fine fabrics.

Furthermore, the invention among other features contemplates the production of a device of the above stated character wherein 20 the auxiliary frame by being pivotally connected in the main frame permits the movement of the auxiliary frame to opposite sides of the main frame when desiring to present the rubbing board for use.

25 With the above and other objects in view, the invention consists in the novel features, details of construction and combination of parts which will hereinafter be more fully set forth, illustrated in the accompanying 30 drawing and pointed out in the appended claims.

In the drawings:

Figure 1 is a front view of a wash board constructed for use;

35 Fig. 2 is a rear view;

Fig. 3 is a vertical section taken through Fig. 1;

Fig. 4 is a view similar to Fig. 3 illustrating a section taken through Fig. 2 of the 40 drawing;

Fig. 5 is a section taken on line 5—5 of Fig. 1;

Fig. 6 is a detail vertical section of the rubbing board; and

45 Fig. 7 is a side elevation of the board illustrating the path of movement of the frame in dotted lines.

Referring more particularly to the accompanying drawings, in which like characters 50 of reference refer to corresponding parts in the several views, 5 denotes the wash board generally comprising a main frame 6 made of wood or the like material and formed with a pair of spaced parallel side rails 7 connected to one another through the medium of a top rail 8. Secured to the con-

fronting faces of the side rail 7 at a point adjacent the lower ends thereof are bearing plates 9 for a purpose to be hereinafter more fully set forth. Mounted on a central line 60 within the main frame 6 is a backing denoted by the character 10 forming between the outer face of the backing and the outer vertical edges of the side rail 7 channels designated respectively by the characters 11 and 12. The bearing plates 9, better illustrated in Figs. 3 and 4 of the drawings are shown as secured at a point beneath and in spaced relation with the lower edge of the back 10 beneath the lower open ends of the channel-shaped spaces 11 and 12. Provided in each of the bearing plates is a transverse slot 13 in which are journaled the outwardly bent trunnions 14 provided on the lower extremities of the U-shaped auxiliary frame 15. 70 The heretofore referred to auxiliary frame 15, owing to its specific configuration, presents spaced parallel side limbs 16 connected to one another at their upper extremities through the employment of a connecting bar 17. The fact that the trunnions 14 of the frame are loosely journaled in the slots 13 of the bearing plates 9, renders the frame capable of being swung in the complete arc 75 of a circle, as clearly shown in Fig. 7 of the drawing, to reverse the position of the frame from, for example, the channel 11 into the channel 12. This idea of connecting the auxiliary frame within the main frame is necessary, as I contemplate the construction of a rubbing board 18 for the cleansing of coarse and delicate fabrics. In order to carry out the object sought for, I construct the rubbing board of a single piece of corrugated metal or the like material and provide 80 the face 19 of the rubbing board of a coarser mesh than is the face 20 thereof. The connection of the rubbing board with the auxiliary frame 15 is accomplished by curling the opposite vertical edges thereof around and in embracing relation with the spaced parallel side limbs 16 of the frame. This rubbing board 18 is of a length lesser than the length of the auxiliary frame and terminates slightly below a transverse slot 21 85 formed in the upper portion of the backing 10. 90

The character 22 indicates a pair of in-turned trunnions formed on the legs 16 of the auxiliary frame at a point opposite and in transverse alinement with the slot 21 and journaled on said trunnions for rotary 100 105 110

movement is a rectangular shaft 23. A T-shaped locking element 24 has its shank 25 loosely projected through the medial portion of the rectangular shaft 23 to adapt the 5 head portion 26 thereof to be inserted through the elongated slot 21 when the auxiliary frame is seated within the channeled space 11 of the board, upon the reversing of the frame to present its finer 10 meshed face 20 for active use, the auxiliary frame is swung in the arc of a circle, the shaft 23 rotated within the auxiliary frame 15 to bring the head 26 of the locking member in alinement with the slot 21 of the backing, permitting the head to pass through the slot and be turned crosswise or at right angles to the slot, consequently establishing a connection of the auxiliary frame with the backing to prevent any accidental swinging 20 movement thereof.

A soap holder 27 constructed from a single blank of sheet metal is mounted on the shaft 23 for an oscillating swinging movement embodying a broad horizontal top wall 28 and spaced triangular side walls 29. The free edges of the side walls and top portion of the soap holder 27 are bent inwardly and in spaced relation with the walls to provide at opposite sides of the side walls 30 29 a pair of grooves 30 and a second pair of grooves 31, in which the upper extremity of the auxiliary frame 15 contacts for limiting the movement of the soap holder in one direction. This construction further facilitates the reversing of the soap holder to assume an active position upon the adjustment of the auxiliary frame 15.

From the foregoing description, taken in connection with the accompanying drawing, 40 the advantages of construction and the method of operation will be readily ap-

parent to those skilled in the art to which the invention relates, and while I have described the principles of operation of the invention, together with the device which I 45 now consider to be the best embodiment thereof, I desire to have it understood that the device shown is merely illustrative, and that such changes may be made when desired as are within the scope of the ap- 50 pended claims.

Having thus described the invention, what is claimed as new, is:—

1. In a wash board, the combination with a main frame having a backing provided 55 with an elongated slot, of an auxiliary frame pivotally mounted in the main frame, and a rotatable member carried by the auxiliary frame and adapted to project through the slot of the backing for holding the auxiliary frame to either side of the backing.

2. In a wash board, the combination with a main frame having a backing, of slotted bearing plates secured to the frame in spaced relation with the lower edge of the 65 backing, an auxiliary frame pivotally mounted in the bearing plates and adapting the frame to be swung to opposite sides of said backing, and a rubbing board connected with said auxiliary frame.

3. In a washboard, the combination with a main frame having mounted therein on a central line a backing providing within the frame a pair of channels, slotted bearing plates secured to the frame below said backing and below the lower ends of said channels, of an auxiliary frame pivotally mounted in the bearing plates and adapted to be swung into either of the channels of the main frame.

In testimony whereof I affix my signature.
JERRY M. LAPLHAM.
